ROOF CONTAINER

Neil M. Loney, Huntington Woods, and William E. Van Berg and Otto Ferguson, Detroit, Mich., assignors to General Motors Corporation, Detroit, Mich., a corporation of Delaware

Application July 16, 1937, Serial No. 153,902

9 Claims. (Cl. 211—13)

This invention has to do with the shipment of sheet metal panels or the like and is concerned especially with the loading for transportation of formed roof decks of automobile bodies.

5 In the automobile body industry where the body assembly plant is located at a distance from the press shop there arises the problem of proper packing of stamped panels in the freight car or other conveyance to avoid damage in transit 10 and handling and to make best use of the space available for loading the panels in large numbers.

Accordingly it is here proposed to fit to the conventional freight car a number of removable containers which in the interest of durability 15 and continuous re-use, together with light weight and low cost of dunnage, are constructed of structural steel members welded together, each container comprising a pair of sides spaced apart a distance substantially corresponding to the 20 width of an individual panel to be loaded, to locate therebetween a succession of panels separately and vertically hung from the sides by a series of suspension hangers arranged in pairs for engagement with the opposite edges of the 25 respective panels. Handling of the panels is facilitated and labor reduced inasmuch as the containers may be loaded and unloaded conveniently outside the freight car and the loaded container moved to and from stowed position.

30 Among the objects of the invention is the provision of an improved hanger and mounting therefor. Accordingly, each hanger comprises a forked hook to engage an offset portion at the edge of the panel about midway of its vertical 35 height and the hook has camming surfaces thereon partly in the form of a flared entrance mouth to facilitate reception and guidance of the offset to seated position. Separate pivotal 40 mountings for each fork enables the forks on opposite sides to be swung in succession between an operative load carrying position and an inoperative position out of interference to the passage of panels into and out of the container through an open end.

45 A further object of the invention is to provide an improved holding device to guard against shifting and displacement of loaded panels. A number of such devices are employed in vertically spaced relation with the suspension hooks 50 and each includes an operating handle and a shiftable member to engage one of a group of panels and by its movement to draw together the adjacent ends of the panels in the group and thereby securely locate the several panels 55 through their contact one with another.

Additional objects and advantages of the invention will become apparent during the course of the following specification having reference to the accompanying drawings wherein Figure 1 is an elevation of a loaded container; Figure 2 is an end view of the container; Figure 3 is a detail perspective view of a few of the suspension hangers; Figure 4 shows the clamping mechanism and is a view looking in the direction of the arrows on line 4—4 of Figure 2; Figure 5 is a sectional view taken on line 5—5 of Figure 1; Figure 6 is a view looking in the direction of the arrows on line 6—6 of Figure 2; Figure 7 is an enlarged detail view of two adjacent hangers; Figures 8 and 9 are detail perspectives of the panel clamping mechanism in operative and inoperative positions, respectively; Figure 10 shows the clamp engaged with the roof and Figure 11 is a section taken on line 11—11 of Figure 1.

20 In the drawings the outline of a freight car in cross section is shown in Figure 1 wherein 2 indicates the floor, 3 the roof and 4 and 5 the side walls. A loaded container is shown in position in the car, the containers being so constructed and proportioned that each is substantially as long as the car is wide and when placed side by side in succession about nine containers 25 will fill a standard size freight car. Each container is intended to hold approximately forty- 30 two roof decks positioned vertically and individually suspended.

25 Each container consists of a skeleton framework and the bottom is supported upon the floor by shoes 6—6. At suitable spaced intervals cross 35 bars 7 connect a pair of longitudinal I-beams 8 which together form a rectangular base. At the four corners of the base, gusset plates 9—9 support vertically extending posts 10 also of I-beam or channel section, and the posts on the two sides 40 are connected at vertically spaced intervals by the longitudinal rails 11, 12 and 13. At one end the container is closed by a removable gate comprising cross members 14—14 and vertical members 15—15. The end gate is removed to facilitate 45 loading. It is held in place by a series of bolts 16 passing at vertically spaced intervals through alined openings in the side bars 15 and the web of the adjacent post 10, each having a slotted end to receive the wedge 17, all as shown in Figure 5. 50 The bolt 16 also passes through a spacer sleeve 18 welded to the web of the post 10. The opposite end of the container may be closed by a similar structure preferably fixedly secured to the adjacent vertical posts 10—10. 55

The roof decks 19, as seen in Figure 1, are stamped metal panels which are curved both longitudinally and transversely. Along opposite side edges a molding bead 20 is formed to constitute in cooperation with the gutter piece 20a welded thereto, a drain channel or drip molding when the panel is assembled as an automobile body top. In the forward portion of its length the bead 20 carries an angular offset comprising a 5 downturned portion 21 and an inturned flange 22. When placed in a vertical position the lower edge of the offset is utilized for the suspension of the panel.

This is shown best in Figure 3 where the lower 15 edge of the offset rests upon one end of a pivoted hanger 23 resting upon the bottom flange of the angle rail 12. The end which seats the panel offset has an upwardly open fork constituted by a 20 pair of tines 24 and 25 bent away from each other toward the top so as to provide an upwardly opening flaring entrance mouth to receive the portion 21 of the offset. In addition the side face 26 of the tine 24 which engages with the inturned flange 22 of the offset tapers upwardly or recedes 25 in a direction opposite to a correspondingly inclined face 27 on the tine 25 and which engages the inturned portion of the bead 20. The surfaces 26 and 27, therefore, provide cooperating cam faces which in conjunction with the flaring entrance mouth of the fork facilitates easy insertion 30 of the offset and its downward movement to final seating position on the hanger 23. A pair of such hangers, one at each side of the container, serve to support each roof panel individually in 35 the container. The engagement of the roof panels intermediate of their length with the suspension hangers effects a distribution of the load in the sense that the lower half of the panel is suspended in tension and the upper half supported 40 in compression and this avoids the distortion and buckling ordinarily occurring when the panels are rested on their longitudinal or transverse edges.

Inasmuch as these hangers 23 project inwardly 45 in the path of the panel during loading and unloading the pivotal mounting enables them to be swung outwardly out of interference at such times when they are not in use. For this purpose the end of the hanger opposite the fork is welded to a pivot pin 28 mounted in the adjacent upper right flanges of a series of U-shaped stampings 50 29 carried by the base flange of the angle 12. In order to avoid damage to the panels during loading by their engagement with the hard edge of the base flange of the angle 12 a wooden rub rail 55 30 is preferably bolted to the flange and projected inwardly a slight distance beyond the edge. A similar buffer is carried by the angle rail 11.

To prevent displacement of the panels during 60 transit they are clamped against one another in groups. It is proposed after say seven panels are loaded, that they be clamped together and then additional groups of seven are loaded and clamped together in succession. The clamping mechanism is carried on each side of the container by the upper rails 13 and may consist of an over center leverage device as shown in detail in 65 Figures 4, 8 and 9. Engagement with the roof panel is through the drip channel 20a by a hook 31 connected by a link 32 with the hand lever 33. The hand lever is pivoted to a block 34 and in the 70 clamped position of the parts, as shown in Figure 4, the opposite ends of the link 32 have their pivot axes arranged on a line below the axis of the swinging lever 34 so that an overcenter relation 75 is established which resists accidental displace-

ment. In addition a latch 35 pivoted to a bracket 36 is positioned in the path of the hand lever. The pivot mounting for the latch 35 is off-center and toward one side so that normally it hangs downwardly at an angle to the vertical. It is 5 pushed back by its engagement with the descending lever until it is cleared when it returns to locking relation and requires pushing back by hand before the lever can be released.

To guide the hook 31 on a straight line during 10 its movement to and from clamped position it has welded thereon an L-shaped member 37 which embraces the inner edge of the horizontal flange on the angle 13. This member also locates the hook 31 in the path of the drip molding 20a and 15 consequently to facilitate passage of the roof panels in and out of the container it is desirable that the clamping mechanism be shiftable laterally beyond the flange edge and held within the vertical limits of the angle member 13. Accordingly 20 the pivot connections between the parts are loose or sloppy and this enables the member 35 to be disengaged with the edge of the angle 13 and placed above the inturned flange. To hold the parts outwardly the hand lever 33 is thrown 25 behind an angle clip 38 which through its frictional engagement prevents accidental displacement of the handle during return shipment of the empty container and during the loading and unloading of the panels. 30

In order that the container may be universal for use with panels of different dimensions, it is proposed that the rails 11 and 12 be mounted adjustably for height and width. Accordingly, these rails at each side form a subassembly unit 35 and are joined at their ends to the vertically disposed angle irons 39 and are braced by diagonal struts 40. The two subassemblies along opposite sides can then be fastened to the corner posts 10 at the desired vertical and transverse position by 40 a series of bolts and nuts as at 41 in Figure 11, passing through aligned openings in the inturned leg of each angle 39 and its adjacent post 10. In the illustrated embodiment, the post contains three groups of four openings, respectively offset 45 vertically and transversely for selective alignment with corresponding holes in the angle iron. The outer and lowermost group is for fastening the side frame to accommodate sedan roofs, the intermediate group positions the frame as shown for coach roofs, and the inner and uppermost group locates the frame for coupé roof panels, the variation in height being determined by the interruption or termination of the offset side 50 flanges 21—22 in the individual types of roof panels.

We claim:

1. A shipping container for containing a number of vertically positioned automobile roof panels which have shouldered offset portions along opposite sides, said container comprising a pair of spaced side walls and a pair of end walls, detachable connections between one of said end walls and the side walls to enable loading and unloading of roof panels through an open end of the container, longitudinal successions of forks carried by the side walls and arranged so that each fork cooperates with an oppositely disposed fork and the forks of each pair provide locating hangers to suspend a roof panel through engagement with its offset portions, means pivotally mounting said forks for outward swinging movement, and a series of overcenter clamping devices carried by each side wall for engagement, respectively, with 65 70 75 80 85 90 95 100

a given panel of a group to draw together the panels of the group.

2. In a shipping container for sheet metal panels or the like, a pair of spaced side members, 5 a pair of panel suspending elements carried by said members and adapted to engage the opposite sides of a vertically positioned panel, additional pairs of panel suspending elements carried in spaced succession by the side members for individually suspending other panels, and a series of clamping devices shiftable longitudinally of said side members for engagement with individual panels of successive groups to clamp the panels together in groups.
- 15 3. Means to suspend vertically a succession of sheet panels, including a container having side walls spaced apart a distance substantially corresponding with the width of the panels, panel suspending hooks arranged in pairs on the side walls and each pair being adapted to engage opposite edges of a panel intermediate the top and bottom thereof, and means movably mounting the hooks for movement between load suspending position and an inoperative position out 20 of interference to the loading and unloading of successive panels.
- 20 4. A shipping container to contain a number of vertically disposed metal panels, having a pair of spaced sides and an open end through which the 25 panels may be passed in succession, a pair of panel suspending hooks carried by said sides to engage the opposite edges of a panel, additional pairs of hooks to suspend other panels, and means pivotally mounting said last named hooks on said 30 sides for their individual swinging movement to inoperative positions so as not to interfere with the passage of the panels to and from suspended position through the open end.
- 35 5. In a shipping container to contain a number of vertically disposed panels, a pair of spaced sides to receive the panels therebetween, a series of upwardly opening forks carried by said sides and arranged in pairs to engage the panels along opposite edges and suspend the same, each fork 40

having a pair of outwardly flaring tines, one of which also has one side inclined laterally in one direction and the other of which has the opposite side inclined laterally in the other direction.

6. In a shipping container having spaced sides, 5 devices on said sides for cooperation in pairs to suspend individual panels of a group in vertical position successively, means to clamp a group of panels together including a movable member engageable with one panel and by its movement 10 drawing the group of panels together, and over-center linkage for holding said member in adjusted position.

7. In a shipping container having spaced sides, 15 devices on said sides for cooperation in pairs to suspend individual panels of a group in vertical position successively, means to clamp a group of panels together including a movable member engageable with one panel and by its movement drawing the group of panels together, an operating lever for said member and means to lock the 20 lever in member clamping position.

8. For shipping sheet metal panels or the like, a container adapted to receive a succession of panels through an open end, devices on opposite 25 sides of the container arranged in pairs for individually suspending the panels in upright positions successively through engagement with opposite edges of the panels intermediate the top and bottom thereof and panel engaging means shiftable longitudinally of the container in vertically 30 spaced relation to said devices for clamping suspended panels together.

9. In a shipping container for sheet metal panels or the like, a pair of spaced frames adapted 35 to receive vertically disposed panels therebetween, seating devices carried by said frames to engage and suspend the panels along their opposite edges and means adjustably mounting said frames in selective vertical and transverse positions to 40 accommodate panels of different types.
